PHONOGRAPH PICKUP DEVICE

Ralph M. Heintz, Cleveland, Ohio, assignor, by
mesne assignments, to Jack & Heintz Precision
Industries, Inc., Cleveland, Ohio, a corporation
of Delaware

Application May 5, 1945, Serial No. 592,183

6 Claims. (CL. 179—100.41)

1

The present invention relates in general to electromagnetic transducer devices, or pickup units, for converting mechanical motion into electrical voltages and more particularly to improvements in such devices as applied to phonograph and vibration pickups and the like.

One of the primary objects of the invention is to provide an improved moving conductor and method of making and assembling the same in a working pickup unit to provide a simple, inexpensive and efficient pickup unit whose voltage generating element is of simplified construction of minimum weight and whose resilient mechanical suspension is inherently free to move transversely and rigid against vertical movement and whose conductor generating element develops voltages only in response to such transverse motion of the suspension.

The present invention, as applied for example to a phonograph pickup unit, utilizes the well known principle of generating electrical voltages by moving a conductor in a magnetic field at right angles to the direction of flux by which the voltages will be proportional to the velocity of mechanical movement.

Briefly the invention contemplates the stamping and subsequent bending of a single continuous piece of sheet metal so as to form its own spring suspension and the mounting of it on a frame through a continuous magnetic iron core in such a manner as to form a single turn around the transformer core. The transformer core also has wound around it a coil having many times the impedance of the single turn voltage generating loop. A permanent magnet is mounted in such a manner as to provide the magnetic flux through which the conductor moves.

With the foregoing and other objects in view the invention resides in the combination of parts set forth in the following specification and appended claims, certain embodiments thereof being illustrated in the accompanying drawings, in which:

Figure 1 is a view in perspective of one form of phonograph pickup unit employing two conductors for voltage generation;

Figure 2 is a view in plan of the punched out sheet metal blank before bending to form a pickup loop;

Figure 3 is a view in perspective of the blank after being bent to form the pickup loop;

Figure 4 is a fragmentary view in perspective view of another type of pickup loop showing the same and the needle partly broken away;

Figure 5 is a plan view of the stamped out blank

2

prior to bending to form the pickup loop of Figure 4;

Figure 6 is a view in elevation of the needle, or stylus, and its holder in vertical section;

Figure 7 is a plan view of another modified form of stamping prior to bending to form a pickup loop;

Figure 8 is a view in perspective of the stamping of Figure 7 bent to form a pickup loop; and

Figure 9 is a view in perspective of another form of phonograph pickup unit employing a single conductor for voltage generation and a loop of the type of Figure 8.

Referring more particularly to the drawings, Figures 1, 2 and 3 show successive stages in the formation of one form of phonograph pickup unit. Figure 2 shows a one piece stamping of sheet metal having preferably the proper electrical conductivity and mechanical strength.

Such a metal may be one of the various aluminum alloys such as 17S, 24S, 75S or one of the beryllium aluminum. It may also be one of the beryllium copper alloys or copper-nickel-manganese alloys. The thickness of the sheet may range from as low as from .002 to .008 inch depending upon the specific gravity, the electrical conductivity and elastic properties of the alloy.

The form of pickup unit shown in Figure 1 includes a supporting frame 1 of non-conducting

material for supporting a two pole permanent magnet 2 and a vertically spaced soft iron magnetic backing plate 3 therefor. It also supports a magnetic core 4 and a coil 5. The pickup, generally indicated at 6, is formed by stamping out a single piece flat stamping of sheet metal as shown in Figure 2. This single piece includes two longitudinally extending legs 7 and 8 of unequal length, a cross band 9, a recess 10 and an angular cross band including transverse arms 11 and 12, longitudinal arms 13 and 14 and cross arm 15.

The sheet 6 is then physically bent into the form shown in Figure 3 in which the two legs 7 and 8 and the cross band 15 become vertical elements as well as the end portions 7' and 8' of legs 7 and 8 which are bent inwardly in spaced overlapping relationship.

The pickup in its form of Figure 3 is then secured to the frame by screws 16 passing through legs 7 and 8 and the frame 6 in such a manner that the core 4 passes around the cross band 9 and through appropriate cut-out recesses in the frame so that the coil is positioned longitudinally of the frame. The core is mechanically just short of being a continuous circle but is substantially continuous magnetically. The permanent mag-

net 2 rests on the frame and is longitudinally spaced from the coil. The two pole pieces 17 and 18 of the permanent magnet extend longitudinally of the frame and their bottom surfaces are elevated with respect to the base of the permanent magnet and extend over the legs 13 and 14 of the pick-up loop in spaced relationship. Beneath legs 13 and 14 is mounted a magnetic backing plate 3 which has pole pieces 19 and 20. The means of attachment of the permanent magnet and the magnetic backing plate to the frame may comprise screw bolts 21 and washers 22, or the like. The bent portions 7' and 8' of legs 7 and 8 form a support for a stylus collet, or block, 23 which receives a stylus, or needle, 24 which may be held in position in the collet by the conventional hand knob 25 for operating a set screw for this purpose.

In this arrangement the pick-up loop by attachment to the frame constitutes its own resilient mechanical suspension that is free to move transversely and to a very limited degree about its own longitudinal axis but rigid to resist vertical movement due to the verticality of legs 7 and 8. The positioning of legs 13 and 14 between the pole pieces 17 and 18 and between 18 and 20 constitute legs 13 and 14 as conductors in which the voltages are generated. The permanent magnet develops poles in its pieces 17 and 18 below which the pieces 19 and 20 of the magnetic backing plate 3 serves to complete the magnetic circuit. Since pole 17 has a magnetic polarity opposite to that of pole 18 the voltages generated in legs 13 and 14 of the pick-up loop will be oppositely directed and will therefore be additive since these voltages are generated in a continuous loop which links the magnetic core 4. A voltage will be generated in coil 5 since it serves as a secondary of a transformer having a single turn primary. Thus the loop 6 of Figure 3 when installed in the assembly of Figure 1 serves not only as a continuous electrical loop but also provides a resilient suspension for the stylus 24 that permits transverse movement thereof since the vertical legs 7 and 8 of the pickup loop is transversely flexible. It will be appreciated that it is the desire to limit the generation of voltages to transverse movements of the stylus and the suspension to the exclusion of vertical movements and the minimization of rotational movement of the suspension about its own longitudinal axis.

An alternate form of pickup unit and pickup loop is shown in Figures 7, 8 and 9 wherein only a single conductor element and a single magnetic gap are used. The stamping shown in Figure 7 and in bent form in Figure 8 includes cross pieces 11A and 12 and a single leg 26, as distinguished from the two legs 13 and 14 of Figures 1, 2 and 3. This leg 26 is positioned between the single pole 27 of the permanent magnet 2A and the single pole 29 of a soft iron magnetic backing plate 28 and thus constitutes a single conductor element between the single magnetic gap. This arrangement has some inherent advantages over that shown in Figures 1, 2 and 3 in that the current generating element 26 is virtually coincident with the rotational axis of the suspension making the dimensional clearances less critical in manufacture and assembly and reducing of undesired voltages in response to rotation and any voltages other than those in response to transverse movements.

Figures 4, 5 and 6 are devoted to a modified form of pickup loop which is so formed in a sin-

gle piece by stamping, or punching, and subsequent bending to support in a different manner the insulated stylus, rather than employing the conventional stylus collet of Figures 1 and 9. Here the single piece blank 6B has cross pieces 11B and 12B to support a leg 26A, which is comparable to leg 26 of Figure 9 and for the same purpose. In addition the blank 6B has a tab 30. This blank is then bent into the form shown in Figure 4 in which the legs 7 and 8 are vertical, the extension 7' is bent downwardly and transversely inwardly and tab 30 is vertical. In addition the extension 7' is rolled at 31 and tab 30 is rolled at 32 to form a means of holding and support directly of an insulating cylinder 33 interiorly threaded to receive the screw threads 34 of a stylus 35 having a stylus point 36.

I claim:

1. In an electromagnetic pickup unit for converting mechanical motions into electrical voltages and including a stylus, a permanent magnet and a spaced soft iron magnetic backing plate therefor and a substantially continuous magnetic transformer core and coil therefor and an insulated supporting frame therefor, a single unitary element formed by a flat piece of stamped out sheet metal bent to include vertical suspension portions and horizontal portions therebetween, one of said horizontal portions extending through said core and another extending between said permanent magnet and its backing plate, said element being carried by said frame for supporting said stylus and for comprising a single turn around said transformer and for comprising a conductor for voltages generated by its movement between said permanent magnet and its magnetic backing plate.

2. In an electromagnetic pickup unit for con-

verting mechanical motions into electrical voltages and including a stylus, a permanent magnet and a spaced soft iron magnetic backing plate therefor and a substantially continuous magnetic transformer core and coil therefor and a supporting frame therefor, a single unitary element

45 formed by a flat piece of stamped out sheet metal bent to include vertical suspension portions and horizontal portions therebetween, one of said horizontal portions extending through said core and another extending between said permanent

50 magnet and its backing plate, said element being carried by said frame for supporting said stylus and for comprising a single turn around said transformer and for comprising a conductor for voltages generated by its movement between said permanent magnet and its magnetic backing plate, said vertical portions of said element being adapted to rigidly oppose vertical movements and flexibly permit transverse movements of said stylus.

60 3. In an electromagnetic pickup unit for con-

verting mechanical motions into electrical voltages and including a permanent magnet and a spaced soft iron magnetic backing plate therefor and a substantially continuous magnetic

65 transformer core and coil therefor and a supporting frame therefor, a stylus and a single unitary metallic element carried by said frame for supporting said stylus and having a portion so positioned with respect to said transformer as to comprise a single turn around the same and having a portion extending between said permanent magnet and its magnetic backing plate to constitute a conductor of voltages generated by its movements therebetween.

75 4. In an electromagnetic pickup unit for con-

verting mechanical motions into electrical voltages and including a permanent magnet and a spaced soft iron magnetic backing plate therefor and a substantially continuous magnetic transformer core and coil therefor and a supporting frame therefor, a stylus and a single unitary metallic element carried by said frame for supporting said stylus and having a portion so positioned with respect to said transformer as to comprise a single turn around the same and having a portion extending between said permanent magnet and its magnetic backing plate to constitute a conductor of voltages generated by its movements therebetween, said element being so formed and connected to said frame as to support said stylus rigidly against movement in its plane of suspension and flexibly transversely to permit transverse movement of said stylus.

5. In an electromagnetic pickup unit for converting mechanical motions into electrical voltages and including a stylus, means for creating a magnetic flux and a substantially continuous magnetic transformer core and coil therefor and an insulated supporting frame therefor, a single unitary element formed by a flat piece of stamped out sheet metal bent to include vertical suspension portions and horizontal portions therebetween, one of said horizontal portions extending through said core and another extending through said flux creating means, said element being carried by said frame for supporting said stylus and

for comprising a single turn around said transformer and for comprising a conductor for voltages generated by its movement in the path of said flux, said vertical portions of said element being adapted to oppose movements of said stylus in its plane of suspension and flexibly permit transverse movements of said stylus.

6. In an electromagnetic pickup unit for converting mechanical motions into electrical voltages and including a stylus, a permanent magnet and a spaced soft iron magnetic backing plate therefor and a substantially continuous magnetic transformer core and coil therefor and an insulated supporting frame therefor, a single unitary element formed by a flat piece of stamped out sheet metal bent to include suspension portions and angularly disposed portions therebetween, one of said angularly disposed portions extending through said core and another extending between said permanent magnet and its backing plate, said element being carried by said frame for supporting said stylus and for comprising a single turn around said transformer and for comprising a conductor for voltages generated by its movement between said permanent magnet and its magnetic backing plate, said suspension portions of said element being adapted to rigidly oppose movements in its plane of suspension and flexibly in a plane transverse thereto to permit movements of said stylus in said transverse plane.
